Atty.

Patented June 28, 1927.

UNITED STATES PATENT OFFICE.

JOSEPH HENRY HARDIE, OF MORECAMBE, ENGLAND.

APPARATUS FOR WASHING GLASSES AND LIKE VESSELS.

Application filed January 6, 1927, Serial No. 159,250, and in Great Britain August 6, 1925.

This invention has reference to apparatus for washing glasses and like vessels, and to apparatus of the kind in which the vessel is supported upon a rotatable holder and subjected to the action of jets of water or washing medium upon its interior and exterior.

In known apparatus considerable splashing of the washing medium is caused by the external jets impinging tangentially against the outer surface of the vessel, to effect, or assist in effecting, the rotation of the latter, and the object of this invention is to provide an apparatus in which splashing will be reduced to a minimum.

In apparatus according to this invention the glass or other vessel is rotated entirely by the action of the internal jets which impinge tangentially against the inside surface of the vessel, and the outside surface of the vessel is rinsed by fine sprays which strike the surface radially or substantially radially.

One arrangement of glass washing apparatus in accordance with the invention is illustrated in, and will now be described with reference to, the accompanying drawings in which Fig. 1 is a vertical elevation partly in section of such arrangement, Fig. 2 is an elevation at right angles to Fig. 1, and Fig. 3 is a plan of the bowl.

Referring to the drawings, 4 indicates the bowl mounted by means of a union and nut 5 and connection 6 upon the upper end of a stand pipe 7 provided at its lower end with a water supply connection 8 and a spring-closed tap or cock 9 adapted to be opened by the operation of a foot-lever 10. Within the connection 6 aforesaid is arranged a supply pipe 11 of lesser diameter which extends into the bowl 4 and is provided with a number of tangentially-arranged turbine jets 12 disposed at various levels and opening at different angles to the horizontal. On the supply pipe 11 is rotatably mounted the glass holder which conveniently consists of a number of spring wire arms 13 connected at the top to a frame or the like 14 rotatably mounted on the supply pipe 11 and having their lower ends bent to engage, as shown at 15, in holes in the rim of a disc or the like 16 also rotatably mounted on the pipe 11. The holder may be provided with rubber studs or the like 17 upon which the glass 18 rests (as shown in dotted lines in Fig. 1).

From the connection 6 aforesaid branch pipes 19 lead up the outside of the bowl 4 to sprayers 20 directed into the interior of

the bowl 4 and situated at or near the top thereof for the emission, radially or substantially radially to the glass 18, of fine sprays of water for rinsing same. The sprayers 20 are preferably adjustable about horizontal axes. The waste water passes away from the bowl 4 through outlet holes 4^a into the connection 6 and a waste pipe 21 leading therefrom.

The supply of water to the turbine jets 12 and the sprayers 20 is regulated by means of spring-closed tap or cock 9, whilst a hand-operated tap or cock (not shown) may be provided for regulating the pressure or quantity of water delivered on the opening of the said foot-operated tap or cock 9.

What I claim as my invention and desire to secure by Letters Patent is:—

1. A washer for tumblers or the like, including a bowl, a water supply pipe projecting therethrough and terminating into a plurality of angularly disposed spray nozzles adapted to direct a spray tangentially upon the inner surface of a tumbler placed thereover, a rotary tumbler support mounted to rotate about said supply pipe and support a tumbler to envelope said nozzles, a second supply pipe surrounding said support and adapted to direct a plurality of radial streams of water upon the exterior of a tumbler placed upon said support, and means for connecting said supply lines to a source of water.

2. A washer for tumblers or the like, including a bowl, a water supply pipe projecting therethrough and terminating into a plurality of angularly disposed spray nozzles adapted to direct a spray tangentially upon the inner surface of a tumbler placed thereover, a rotary tumbler support mounted to rotate about said supply pipe and support a tumbler to envelope said nozzles, a second supply pipe surrounding said support and adapted to direct a plurality of radial streams of water upon the exterior of a tumbler placed upon said support, and a single member connecting both of said supply pipes to a source of water, said chamber also having a chamber therein in communication with said bowl to collect the waste water from said bowl and from which the waste water may be conducted away.

In witness whereof I have hereunto set my hand.

JOSEPH HENRY HARDIE.
